UNITED STATES PATENT OFFICE.

CHARLES D. FAGAN, OF SHARON, PENNSYLVANIA, ASSIGNOR TO SHARPSVILLE BOILER WORKS CO., OF SHARPSVILLE, PENNSYLVANIA, A CORPORATION OF PENNSYLVANIA.

DESIGN FOR A GASOLINE-METER CASING.

Application filed July 28, 1927. Serial No. 22,904. Term of patent 14 years.

To all whom it may concern:

Be it known that I, CHARLES D. FAGAN, a citizen of the United States, residing at Sharon, in the county of Mercer, State of Pennsylvania, have invented a new, original, and ornamental Design for Gasoline-Meter Casing, of which the following is a specifica-

Fig. 1 is an elevational front view of a gasoline meter casing showing my new design.

Fig. 2 is an elevational side view thereof on a reduced scale.

I claim:

The ornamental design for a gasoline meter casing, as shown.

CHARLES D. FAGAN.
